UNITED STATES PATENT OFFICE.

ARTHUR TREVOR DAWSON AND GEORGE THOMAS BUCKHAM, OF WESTMINSTER, LONDON, ENGLAND, ASSIGNEES TO VICKERS LIMITED, OF WESTMINSTER, ENGLAND.

SIGHTING APPARATUS FOR ANTI-AIRCRAFT GUNS.

1,360,730.

Specification of Letters Patent. Patented Nov. 30, 1920.

Application filed July 7, 1917. Serial No. 179,267.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements in or Relating to Sighting Apparatus for Anti-Aircraft 10 Guns, of which the following is a specification.

This invention relates to sighting apparatus for anti-aircraft guns in which means are provided for correcting the angle of tangent elevation during the elevation and depression of the gun. In such sighting apparatus it has been suggested to vary the angle of tangent elevation by means of a circular guide which can be adjusted into 15 different degrees of eccentricity with respect to the gun trunnion axis in accordance with the height of the target, the guide thus acting as an eccentric upon the member carrying the sight.

According to the present invention the 20 sighting apparatus is provided with a cam so designed that as the gun is elevated to keep the sight on the target the angle of tangent elevation is automatically altered both for the change of range and the change of angle of sight without its being necessary to ascertain the range. In this manner as the height may (especially in the case of an airship) 25 remain constant for an appreciable length of time notwithstanding constant alterations in the range, we avoid the necessity for constantly varying the preliminary adjustment as the range increases or decreases, with the result that a consequent increase in the 30 accuracy of fire and the rate of fire is obtained. Furthermore it becomes possible to control from a central station the adjustment of the sighting apparatus of any number of 35 guns arranged at considerable distances apart since although the range of the target 40 may be different at each of the guns, the height will naturally be the same.

In the preferred constructional form of our improved sighting apparatus, we employ 45 a cam of the profile type whose position is adjustable to agree with the height of the target and against which bears a roller or projection carried by the sight arm, relative movement between the cam and roller 50 being caused to take place during the eleva-

tion and depression of the gun to automatically alter the angle of tangent elevation as aforesaid.

In order that the said invention may be clearly understood and readily carried into effect we will describe the same more fully with reference to the accompanying drawings, in which:—

Figure 1 is a side elevation viewed from the left hand side of the mounting, showing 65 more or less diagrammatically a constructional form of the improved sighting apparatus.

Fig. 2 is a view similar to Fig. 1, but viewed from the right hand side of the 70 mounting.

Fig. 3 is a view similar to Fig. 1 showing, also more or less diagrammatically, a modified form of the sighting apparatus.

Fig. 4 is a view similar to Fig. 1 showing, also more or less diagrammatically, a 75 further modified form of the sighting apparatus.

Fig. 5 is an end elevation on an enlarged scale of the cam and roller of Fig. 4.

Fig. 6 is a view similar to Fig. 5 showing 80 a modified arrangement of the cam and roller, and

Fig. 7 is a plan view showing the relative 85 positions of the component parts of the sighting apparatus and their connections on both sides of the gun.

A is the carriage and A' the cradle. B is the sight arm pivoted at b to a bracket on the cradle. b' is the roller on the sight 90 arm and B' is the cam upon which the roller bears.

In the example shown by Figs. 1 and 2, the cam B' is pivoted on a suitable pivot B² attached to the left hand side of the carriage 95 and is swung about this pivot, to agree with the height of the target, by a hand wheel b² which is mounted at the right hand side of the mounting and which operates through worm gearing upon a pinion b³ meshing 100 with a segmental rack B³ fixed to the cam B'. The rotation of the handwheel b² angularly displaces a graduated dial b⁴ so that the adjustment given to the cam can be read in terms of height of the target. After the 105 cam B' has been adjusted to the desired position, the gun is elevated or depressed to bring the sight on the target and during this operation the roller b' moves around the cam B' and the required alteration to the 110

angle of tangent elevation is automatically effected. In the example shown the sight arm carries a check roller b^x engaging in a cam groove B^x in the cam B' .

5 The sight bar or carrier B^4 on the left hand side of the cradle is connected by a deflection pivot b^5 to an intermediate bar B^5 pivoted to the sight arm B co-axially with the pivot b . Interposed between the 10 sight arm B and the intermediate bar B^5 is suitable gearing operated by a handwheel b^6 for elevating or depressing the sight in relation to the sight arm to effect vertical spotting corrections and interposed between the 15 intermediate bar B^5 and a rearward extension of the sight bar is gearing operated by a handwheel b^7 for deflecting the sight to effect lateral deflection and spotting corrections. The intermediate bar B^5 is cross-connected to a bracket B^6 on the right hand side of the cradle and the sight bar B^7 on this side of the cradle is pivoted by a deflection pivot b^8 to the said bracket and is cross connected by a rod B^8 to the rearward 20 extension of the sight bar B^4 on the left hand side of the mounting.

A pointer C (see Fig. 2) may be provided which moves across the face of the dial b^4 as the gun is elevated. The face of the dial 30 may be marked with curves giving the true range or equivalent time of flight or the fuse number for the particular height to which the dial has been adjusted, in conjunction with the angle of sight. The reading observed against the pointer may be used for the purpose of setting the shell 35 fuses. The said pointer may form part of a link C' pivoted at C^2 to the cradle and formed with a slot engaging with a pin C^3 on a bracket attached to the carriage.

The modified construction shown by Fig. 3 is similar to Figs. 1 and 2 except that the cam B' is mounted on the cradle and is caused to move with respect to the gun 45 through an angle equal to the angle of elevation of the gun, by a link b^9 pivoted at its forward end to a bracket a on the carriage and at its rear end to an arm B^9 pivoted at B^2 to the cradle carrying the height setting gear. The link b^9 and the arm B^9 are so 50 arranged that a parallel motion arrangement is provided for maintaining the cam B' at a fixed angle in space during the elevation and depression of the gun, subject of course to any adjustment that may be given thereto by the hand wheel b^2 . The broken lines in Fig. 3 show the position of the cam when the gun is pointing at the maximum 55 angle of elevation. Instead of the link b^9 suitable gearing may be employed for obtaining the same result. In this construction the check roller b^x and the groove B^x of Figs. 1 and 2 are not employed, the roller b' being held in firm contact with the cam 60 by a spring operating on the sight arm.

In Figs. 4 to 6 a surface cam attached to the carriage is employed instead of a profile cam as in Figs. 1 to 3 and in this case the adjustments for different heights instead of being effected by angularly displacing the cam is effected by causing relative lateral movement to occur between the roller b' and the cam by a handwheel b^{2x} so as to bring the roller on the lamination of the cam corresponding to the particular height of the target. In Figs. 4 and 5 the roller b' is moved across the cam and in Fig. 6 the cam is movable laterally with respect to the roller.

The cam of Figs. 1 and 3 may be so constructed as to also impart to the sight the correct angle of lead or vertical deflection for a target advancing toward or receding from the gun position, allowing for the varying time of flight for the changing range. For this purpose the cam would be adjustable angularly for different heights as described with reference to Figs. 1 and 3, but instead of being of the profile type it would be of the surface type; the center lamination of the cam would correspond to no speed of the target and the laminations to each side of this center lamination would correspond to targets advancing toward or receding from the gun position at different speeds, means being provided for effecting relative lateral movement between the roller and the cam to bring the desired lamination into use.

What we claim and desire to secure by Letters Patent of the United States is:—

1. In sighting apparatus for anti-aircraft guns, the combination of a sight and means for elevating and depressing the gun to keep the sight on the target, with means comprising a cam for automatically altering the angle of tangent elevation during the elevation and depression of the gun, for both the change of range and the change of angle of sight without ascertaining the range.

2. In sighting apparatus for anti-aircraft guns, the combination with the sight arm, of a cam upon which the sight arm bears, means for adjusting said cam in accordance with the height of the target and means for causing relative movement to take place between the sight arm and the cam during the elevation and depression of the gun so as to cause the cam to effect the required correction in the angle of tangent elevation.

3. In sighting apparatus for anti-aircraft guns, the combination with the sight arm mounted on the gun cradle, of a cam upon which the sight arm bears, and means for adjustably connecting said cam to the gun carriage so as to enable its position to be altered in accordance with the height of the target.

4. In sighting apparatus for anti-aircraft guns, the combination with the sight arm,

G. Hartman

- of a surface cam upon which the sight arm bears, means for adjusting said surface cam in accordance with the height of the target and means for causing relative movement to take place between the sight arm and the surface cam during the elevation and depression of the gun so as to cause the surface cam to effect the required correction in the angle of tangent elevation.
5. In sighting apparatus for anti-aircraft guns, the combination with the sight arm, of a surface cam, a roller on said sight arm for bearing upon said cam, means for effecting relative lateral movement between the roller and the cam to bring into operation the surface or lamination of the cam corresponding to the ascertained height of the target and means for causing the roller to travel in contact with said surface or lamination during the elevation and depression of the gun.
10. 6. In sighting apparatus for anti-aircraft guns, the combination with a cam device capable of adjustment, to agree with the height of the target and serving during the elevation and depression of the gun to automatically vary the angle of tangent elevation, of means actuated by said cam device for automatically indicating the true range of the target or equivalent time of flight of the projectile or the fuse number.
15. 7. In sighting apparatus for anti-aircraft gun, the combination with a cam device capable of adjustment to agree with the height of the target and serving during the eleva-
- tion and depression of the gun to automatically vary the angle of tangent elevation, of a member marked with curves, means for moving said member by the adjustment given to the cam device, a pointer, and means for causing said pointer to move across said member during the elevation and depression of the gun.
20. 8. In sighting apparatus for anti-aircraft guns, a sight and means for imparting to the sight the correct angle of lead or vertical deflection for a target advancing toward or receding from the gun, comprising a cam device adapted to be adjusted to agree with the height of the target and to serve during the elevation and depression of the gun to automatically vary the angle of tangent elevation.
25. 9. In sighting apparatus for anti-aircraft guns, the combination with the sight arm, of a surface cam, a roller on said sight arm for bearing against the cam, means for angularly adjusting said cam to agree with the height of the target, and means for causing relative lateral movement to occur between the cam and the roller to agree with the speed of a target advancing toward or receding from the gun.

In testimony whereof we have hereunto affixed our signatures.

ARTHUR TREVOR DAWSON.
GEORGE THOMAS BUCKHAM.
